Joseph J. Cosin, Brooklyn, N. Y.

Application May 6, 1949, Serial No. 2,479

Term of patent 7 years

(Cl. D58—11)

To all whom it may concern:

Be it known that I, Joseph J. Cosin, a citizen of the United States of America, residing in Brooklyn, county of Kings, and State of New York, have invented a new, original, and ornamental Design for a Package, of which the following is a specification, reference being had to the accompanying drawing, forming part thereof in which:

I claim:

The ornamental design for a package, as shown.
JOSEPH J. COSIN.
